UNITED STATES PATENT OFFICE.

JOHN T. CULLEN, JR., OF CLINTON, IOWA.

STEAM BOILER.

Application filed August 4, 1922. Serial No. 579,723.

This invention relates to steam boilers of the type in which there are a plurality of water tubes arranged in parallelism between two headers with which said tubes are in communication and which are connected above the tubes by a water drum.

Objects of the invention are to provide a boiler which may be constructed at a minimum cost, which will afford a large storage space for steam, which will reduce priming or foaming within the boiler to a minimum, in which the picking up of water with the steam will be substantially prevented, and in which the circulation of water through the tubes is facilitated. Other objects are the provision of a boiler having a high degree of safety and which is so constructed as to dispense largely with brace members and other supports. Other objects and advantages of the invention will be apparent from the following description and appended claim.

The accompanying drawing represents an embodiment of the invention and shows in longitudinal section a steam drum, water tubes, and the connecting headers in relation to a furnace.

Referring to the drawings in detail, 1 designates the front and rear walls of the furnace having a grate 2 at its front end. Positioned above the grate and resting upon the walls 1, is a boiler constructed according to the present invention. The boiler is provided with front and rear headers 3 and 4 which are so positioned that the header 3 will be at a greater elevation than the header 4, in order to afford an inclination of water tubes, 5, which may be of any suitable number and shape and which communicate at their ends with the interior of the headers.

Above the water tubes, is a drum 6, which likewise communicates at its ends with the headers 3 and 4 and which comprises two substantially frusto-conical sections 7 and 8, joined together at their larger bases and having their smaller bases connected, respectively to the headers 3 and 4. The drum is arranged with its lower side sloping in parallelism with the water tubes between headers 3 and 4, while the upper side of section 7 lies in a substantially horizontal plane and the upper side of section 8 is inclined abruptly downward from juncture of the two sections. A connection 9 having a steam outlet 10 is connected to the upper side of section 7, adjacent the juncture of the two

sections and is located about twice as far from header 3 as from header 4, the length of the section 7 being about twice that of the section 8.

In this connection it will be noted that the connection 9 is located at the point in the drum where the storage space for steam is greatest, and that the sections 7 and 8 are connected to the sides of the headers 3 and 4 whereby free circulation of the fluid is provided for.

The water in the tubes 5 circulates toward the front header 3 whence it passes with absolutely no constrictions into the steam drum. It will be noted that the steam drum 7 gradually increases in diameter rearwardly from the front end of the boiler to a point approximately two-thirds of the distance from its forward end to the steam outlet, and, since the bottom of the drum is parallel with the tubes, the water passes freely from the forward end to the rear end of the drum in the best condition to liberate steam. The area of the surface of the water in the drum is ample to permit the steam to be quietly liberated even when boiler is being forced beyond its rating. Dry steam is thus disengaged without entrained water. By reason of the large area of the surface of the water in the conical drum the liberated steam contains a minimum of moisture.

The large steam storage space afforded by the drum below the steam outlet is an important feature in connection with the extreme fluctuation of pressure. These fluctuations in boilers now in common use are a source of violent foaming or priming when the flow of water is constricted by small openings from header to drum and violent circulations are induced by excessive angle of tubes. The drum 7, as it gradually increases in size from its front end to a point approximately two-thirds of the distance between its front and rear ends, affords plenty of steam room close to the outlet. The steam is drawn from the front end of the boiler toward the steam outlet and, since water seeks its own level, the water in this boiler gives sufficient head to the tubes and avoids danger of blistered, burned and bagged tubes.

On account of the shape of this drum the boiler can be manufactured at a minimum cost as to labor and material, and since the drum is of a conical type with absolutely no flat surfaces, the use of braces, such as are necessary in those types of boilers with which

it has been attempted to attain the same results as are obtained by the conical drum of the present invention is dispensed with. In the boiler of the present invention the 5 steam outlet is located right at the point where the storage space of the steam is the largest, and on account of the construction of the upper portion of the boiler itself and the abrupt inclination of the top of the rear 10 portion of the drum from the steam outlet, the steam, in the operation of the boiler is always drawn with the flow of the water. Thus the picking up of water with the steam is avoided and the circulation of the water is 15 speeded up, giving the boiler added efficiency.

It will also be noted that the rear header 4, is connected with the drum in such a manner that a steam trap will not be formed 20 in the upper portion of said header and that the connection between the drum and the headers is such that there will be a free circulation of the liquid contained therein, because the liquid will fill the rear header sub- 25 stantially to its top, whereas the water level in the front header 3, and in the section 7 of the drum will be considerably below the top

thereof, thus affording a space for the escape of steam from the liquid and its collection prior to being led off through the steam outlet 10 in the connection 9.

What is claimed as new is;

A steam boiler comprising a pair of headers, a plurality of tubes connecting said headers, said tubes being inclined with respect to the water level within the boiler, a steam drum formed of a pair of frusto conical sections each having its smaller end secured to and communicating with one of said headers, said sections being secured together at their larger ends, the lower side of said drum lying below said water level and being inclined in the direction of the tubes, the conicity of that section of the drum which is adjacent the elevated ends of the tubes being such that the upper wall of said section does not incline below a horizontal plane, said drum having a steam outlet in its upper wall adjacent the large ends of said sections.

In testimony whereof I have hereunto set my hand.

JOHN T. CULLEN, JR.
